UNITED STATES PATENT OFFICE.

JOHN EDWARD SHERMAN, OF WORCESTER, MASSACHUSETTS.

DRINKING-CUP.

1,222,565.

Specification of Letters Patent. Patented Apr. 10, 1917.

Application filed April 27, 1914. Serial No. 834,578.

To all whom it may concern:

Be it known that I, JOHN EDWARD SHERMAN, of Worcester, in the county of Worcester and State of Massachusetts, a citizen of 5 the United States, have invented a new and useful Improvement in Drinking-Cups, of which the following is a specification.

Many varieties of paper drinking cups have been constructed and are now in use, 10 but with the exception of the cups molded in the shape of small tumblers and which are usually made of paper treated with some waterproofing preparation, the cups of which applicant has knowledge are very in- 15 convenient to use. They present a sharp edge to the lips which is apt to cut them. They are wider at the mouth than at the base so that in drinking from them the water is apt to run out from either side of 20 the portion resting on the lips, thus wetting the drinker and his clothes. Moreover, there is no place to accommodate the upper lip.

In my drinking cup below described these 25 faults are corrected, the cup being deep and narrow, having a place to accommodate the upper lip when drinking, means for readily opening the cup and for preventing the lip from being cut while the cup is in use. 30 Moreover, it can be folded flat for trans- portation and in this form is of substan- tially uniform thickness.

Moreover, it has been found that a cup 35 made of ordinary paper will hold water for a sufficient length of time so that a waxed or other especially prepared paper is unnecessary except where the cup is to be preserved, and the preservation of the cup is a thing not desired.

40 My invention will be understood by reference to the drawings, in which—

Figure 1 is a top view of the cup;

Fig. 2 being a side elevation of the cup when open for use, and

45 Fig. 3 a vertical section of the cup in closed position.

The cup is tubular, is closed at one end and comprises an under side A and an upper side B. The edge of the side B, which 50 forms part of the opening or mouth, is cut down as at B¹ so that it is of less height at its middle portion than the side A. The curve of this downward cut is such as to leave at each end portions b¹ of substan- 55 tially the same length as the adjacent edge of the under side A. These portions b¹

serve as the side walls of a trough formed by the edge a when the cup is in use and prevent the water from trickling out at the ends of the drinking edge. The middle portion of the cut, i. e., that between the portions b¹ is shaped to form a recess which will fit over the upper lip. The corresponding edge of the side A has a reinforce A¹ which is folded over and turned down inside the cup and preferably is sealed against the inside wall of the side A, thus forming a double edge a which extends along the entire upper portion of the side A, or at least so much thereof as would naturally touch the lips while drinking.

This cup may be constructed in a variety of ways, but as shown it is formed of a folded blank, the central portion of which forms the side A and carries the reinforce A¹, the side portions being cut to form the recess B¹ and folded to overlap as at b and being stuck together. While the sealing of the portion A¹ against the inner wall of the side A is desirable, it is not necessary, and in fact this portion may be turned outside the part A and sealed thereto if thought best. It can be made of ordinary paper sealed with gum at but little expense and easily packed in large quantities for trans- portation.

Other ways of constructing this cup will occur to those skilled in the art, the main feature and novelty being the folding over of the part from which one is to drink so as to form a double edge and providing a continuation of this edge at each end thereof such as to hold the water from spilling out when the edge is in use. The cutting away of the side B has not the only advantage as stated above, in that it prevents the side B from touching the user of the cup and at the same time its ends prevent leakage of water at the ends of the edge a, but it also exposes the inner portion of the side A so that when it is desired to open the cup for use the top edge of the side A may be grasped by the thumb and finger of one hand and the side edges squeezed together by the other hand.

What I claim as my invention is:—

A tubular, flexible, paper, drinking cup made from a single sheet of paper the two opposite edges of which overlap and are gummed together to form a flattened tube, said tube being closed at one end, one side of its open end having a curved recess

whereby the opposite edge of said open end will be exposed and may be utilized to open the cup from its flattened position the ends of said curved edge serving as side walls 5 for said cup when in use and said opposite portion having a straight edge and being of double thickness whereby said edge may be applied to the mouth without danger of

cutting the lip, the longest portion of said recessed side being equal in length to the 10 opposite side whereby when in use the liquid will be confined and directed to the mouth.

JOHN EDWARD SHERMAN.
